US00D591419S

(12) **United States Design Patent**
Chandran et al.

(10) **Patent No.:** **US D591,419 S**
(45) **Date of Patent:** **** Apr. 28, 2009**

- (54) **VENTILATION PORTION OF A VENTILATION APPARATUS**
- (75) Inventors: **Sanjay Chandran**, Boca Raton, FL (US); **Shara Hernandez**, Davie, FL (US); **Louis Javier Collazo**, Pompano Beach, FL (US)
- (73) Assignee: **Mergenet Solutions, Inc.**, Coconut Creek, FL (US)

(**) Term: **14 Years**

(21) Appl. No.: **29/290,731**

(22) Filed: **Jan. 8, 2008**

(51) **LOC (9) Cl.** **29-02**

(52) **U.S. Cl.** **D24/110.1; D24/110.4;**
..... **D24/110.5**

(58) **Field of Classification Search** **D24/110.1,**
..... **D24/110.4, 110.5; 128/207.11, 206.11, 207.18,**
..... **128/205.25, 206.21**

(57) **CLAIM**

The ornamental design for a ventilation portion of a ventilation apparatus, as shown and described.

DESCRIPTION

FIG. 1 is a front perspective view of a ventilation interface portion of a ventilation apparatus showing our new design;

FIG. 2 is a left side perspective view thereof;

FIG. 3 is a right side perspective view thereof;

FIG. 4 is a top perspective view thereof;

FIG. 5 is a rear perspective view thereof;

FIG. 6 is a bottom perspective view thereof; and,

FIG. 7 is an enlarged front perspective view of the claimed ventilation interface portion.

The broken line showing of the ventilation interface portion of a ventilation apparatus is for illustrative purposes only and forms no part of the claimed design.

1 Claim, 7 Drawing Sheets
